UNITED STATES PATENT OFFICE.

BAYARD P. SILVER, OF ST. LOUIS, MISSOURI, ASSIGNOR TO F. B. CHAMBERLAIN COMPANY, A CORPORATION OF ILLINOIS.

DESIGN FOR A FOLDING PICTURE-CARD.

48,506.

Specification for Design.

Patented Feb. 1, 1916.

Application filed November 15, 1915. Serial No. 61,694. Term of patent 7 years.

To all whom it may concern:

Be it known that I, BAYARD P. SILVER, a citizen of the United States, residing at St. Louis, State of Missouri, have invented a new, original, and ornamental Design for Folding Picture-Cards, of which the following is a specification, reference being had to the accompanying drawing, forming part thereof.

Figure 1 is a top view of the card, show-

ing my new design, and Fig. 2 is a front elevation of said card.

I claim:

The ornamental design for a folding picture card, as shown.

B. P. SILVER.

Witnesses:

F. H. MILLER,
B. E. MURDOCH.
